SMALL-ASPECT-RATIO WING

Steffen P. Nemeth, Chicago, Ill.

Application December 13, 1935, Serial No. 54,306

6 Claims. (Cl. 244—35)

This invention relates to a circular airplane wing. Such wings have the advantages of being free from spinning tendencies, stall proof, and compact in design. The circular wings so far proposed have however so small a ratio of the lift divided by the drag, at small angles of attack, as to make them impractical.

An analysis of the measured air forces of small-aspect-ratio wings shows now that said low value of the lift divided by the drag is not solely and principally the consequence of a comparatively large drag, as would naturally suggest itself, but it is also and to a dominant extent the consequence of a comparatively small lift. That is to say: at small angles of attack corresponding to cruising speeds, the lift is even smaller than could ordinarily be expected from the experience with large-aspect-ratio wings, allowing fully for the influence of the small aspect ratio as predicted by the ordinarily accepted wing theory. The restrictions of aerodynamic theory do not stand in the way of a larger lift under the same flight conditions. The present invention provides for a small-aspect-ratio wing having a lift larger than that of ordinary small-aspect-ratio wings, approaching the lift predicted by theory.

The relation between the magnitude of the lift and the angle of attack of ordinary wings of different aspect ratios is well illustrated in the diagrams on page 5 of Report No. 431 of the National Advisory Committee for Aeronautics, entitled "Characteristics of Clark Y Airfoils of Small Aspect Ratios", by C. H. Zimmermann. The solid curve in figure 2 on that page is practically straight in the region of small angles of attack, indicating thereby that the rate of change of the lift in relation to the angle of attack is constant. That curve relates to an aspect ratio of 6. The corresponding curves referring to small aspect ratios are however bent up. The rate of lift increase is thereby indicated to be deficient at small angles of attack. My invention provides for a small-aspect-ratio wing with a nearly constant rate of lift increase at small angles of attack.

My invention resides in the discovery that a wing with circular planform, notwithstanding its small aspect ratio, creates a full lift, and one proportional to the angle of attack, if composed of at least two portions, a major front portion, and a minor rear portion, said rear portion being vertically staggered with respect to the front portion so that the leading edge of the rear portion is positioned below the trailing edge of the front portion, and separated therefrom by an open gap.

My invention provides accordingly for a circular

compound wing characterized by a substantially straight lift curve as contradistinguished from a sagging lift curve.

Such compound circular wing would in addition naturally possess all advantages flowing from that arrangement for all wings, whatever their aspect ratio may be. The arrangement lends itself easily for using the outer portions of the rear wing portion as ailerons, and the center portion as a flap, so that at large angles of attack the latter may be turned down about a transverse axis into contact with the front wing portion, and the burbling of the airflow may thus be delayed and a somewhat larger maximum lift obtained. For at large angles of attack the lift deficiency of a small-aspect-ratio wing is not pronounced and its amelioration by my novel arrangement not urgent. The adoption of my circular wing structure is however not predicated on the experience with large-aspect-ratio wings because with them there is no opportunity for the principal useful effect of my arrangement, namely to make the lift proportional to the angle of attack, whereby a large efficiency of a small-aspect-ratio wing is obtained, because large-aspect-ratio wings create a lift proportional to the angle of attack anyhow, even without dividing them up in the characterized manner.

These and other desirable objects and advantages of my invention will be illustrated in the accompanying drawing and described in the specification, a certain preferred embodiment being disclosed by way of illustration only; for, since the underlying principles may be incorporated in other specific devices, it is not intended to be limited to the one here shown except as such limitations are clearly imposed by the appended claims.

In the drawing like numerals refer to similar parts throughout the several views, of which

Fig. 1 represents a vertical cross section through the center of a wing incorporating my invention, on line 1—1 of Figure 2.

Fig. 2 represents a plan view of the same wing as seen from above, and

Fig. 3 represents in a schematic diagram the control system of the several rear portions of the wing.

The wing is composed of a front portion 1 and rear portions 2, 3, and 4. The outer edges of all four portions 1 to 4, seen from above, form a circle 5, 6, 7, 8. The trailing edge 9 of front wing portion 1 is a regularly rounded arc convex to the rear, and has practically the same shape as the leading edges 11, 12 of the rear wing portions,

which portions 2, 3, and 4 in unison are of falcate shape. In vertical section parallel to the direction of flight, as seen in Figure 1, all wing portions are streamline contoured. I have obtained 5 the best results by using streamlined double cambered wing sections, the upper camber line, like 23 having a larger curvature than the lower camber line, like 24, with moderate roundness of the leading edges 5, 11, and 12, which are almost 10 sharp, and with sharp trailing edges 6 to 9, the maximum chord of the front portion 1 being three quarters of the span.

Front wing portion 1 is rigidly secured to the airplane structure in any suitable manner, for 15 instance by being provided with a front spar 14 and a rear spar 15, said spars being held by and rigidly secured to struts 16 of the airplane fuselage not shown in the drawing.

Extending backward from the rear spar 15 are 20 provided arms 17, bent down behind the front wing portion and having at their ends hinges 18 behind and below the trailing edge 9 of the front wing portion. The rear wing portions are hinged at 18 to these arms 17, the axes of rotation extending approximately parallel to the average direction of the portion of the trailing edge 9 in front of the rear portion supported. In their 25 normal flying position, the rear portions 2, 3 and 4 are substantially parallel to the front portion 1 of the wing, and are separated therefrom by the gap 19 extending all along the rear of the front portion and the front of the rear portions of the wing. Trailing edge 9 is disposed substantially 30 on top of and above leading edges 11 and 12. It is separated therefrom by a gap 19 extending all along the rear of the front portion and the front of the rear portions of the wing. I obtained good results by making gap 19 approximately 35 equal to one thirty second of the wing span.

The outer rear portions 2 and 4 may be turned 40 as ailerons by means of the control stick 20 to which they are connected by means of the control cables 21 in any suitable manner, for instance as diagrammatically indicated in Figure 45 3. The rear center portion 3 is connected by similar control cables to an auxiliary hand lever 22 secured against motion while not in use. Turning hand lever 22 turns flap 3 into the position shown in dashed line in Figure 1. In its extreme position, its leading edge 12 is in close vicinity to front wing portion 1 and the gap 19 becomes then very narrow.

This latter is the position of the flap during 50 starting and landing. For cruising, the hand lever 22 is placed so as to move flap 3 into the position shown in solid line in Figure 1. During

all conditions of flight, side portions 2 and 4 are used as ailerons exactly as with conventional airplanes.

I claim:

1. A circular wing having a streamline contoured major front portion and a streamline contoured minor rear portion, said rear portion being in spaced relation to said front portion so that the leading edge of the rear portion is positioned substantially below the trailing edge of the front portion. 5

2. A circular wing having a streamline contoured major front portion and a streamline contoured minor rear portion substantially parallel thereto, said rear portion being in spaced relation 15 to said front portion so that the leading edge of the rear portion is positioned substantially below the trailing edge of the front portion. 15

3. A circular wing having a streamline contoured major front portion and a streamline contoured falcate minor rear portion, said rear portion being in spaced relation to said front portion so that the leading edge of the rear portion is positioned substantially below the trailing edge of the front portion. 20

4. A circular wing comprising a major streamline contoured front portion, a minor streamline contoured flap portion behind the central region of said front portion, two streamline contoured aileron portions behind the two side regions 30 respectively of said front portion, the trailing edge of said front portion being substantially alike to the composite leading edge of said flap and aileron portions forming an arc open to the front, said leading edges of the flap and aileron 35 portions being positioned below and in spaced relation to the trailing edge of the front portion, and means for turning the flap about a transverse axis so as to bring its leading edge into 40 bodily contact with the trailing edge of the front portion. 40

5. A circular wing having a streamline contoured major front portion and a crescent streamline contoured minor rear portion in spaced relation thereto so that the leading edge 45 of the rear portion is positioned substantially below the trailing edge of the front portion.

6. A circular wing having a streamline contoured major front portion and a crescent streamline contoured minor rear portion about 50 one third in area of the front portion and being in spaced relation thereto so that the leading edge of the rear portion is positioned substantially below the trailing edge of the front portion. 55
